UNITED STATES PATENT OFFICE.

WILLIAM R. BLAIR, OF ST. LOUIS, MISSOURI, ASSIGNEE TO LANDIS MACHINE COMPANY, OF ST. LOUIS, MISSOURI, A CORPORATION OF MISSOURI.

AWL-FEEDING MECHANISM.

1,143,683.

Specification of Letters Patent. Patented June 22, 1915.

Application filed February 1, 1915. Serial No. 5,532.

To all whom it may concern:

Be it known that I, WILLIAM R. BLAIR, a citizen of the United States, residing at the city of St. Louis, State of Missouri, have invented a certain new and useful Improvement 5 in Awl-Feeding Mechanism, of which the following is a full, clear, and exact description, such as will enable others skilled in the art to which it appertains to make 10 and use the same, reference being had to the accompanying drawings, forming part of this specification.

This invention relates to leather sewing machines of the general type illustrated and 15 described in U. S. Letters Patent, No. 743,870 to French and Meyer.

The specific feature to which this invention relates is an improvement in the means for adjusting the feed or throw of the awl. 20 As is well known, in such machines the work is fed to the needle by an awl which has a vertical movement in which it operates to pierce the work, and a lateral horizontal movement in which it operates to carry the 25 work along to proper position under the needle.

In the sewing of shoes, it is necessary to have a wide variance in length of stitch, this circumstance being particularly pertinent in 30 recent time due to the popular demand for rubber-soled shoes, which it is necessary to sew with very long stitches. It is understood, of course, that the length of stitch is determined by the extent of lateral feed of 35 the awl, and hence the length of stitch is determined by the adjustment of the awl for the lateral feeding movement.

By reference to the accompanying drawings, in which like characters of reference 40 are used to indicate like parts throughout, it will be understood that Figure 1 represents a detail top view, partly in section, of the awl carrying and operating mechanism, and Fig. 2 is a detail front view of the same 45 parts of the machine.

Referring more specifically to the drawings, it will be understood that 1 represents the awl feed plate which is mounted for lateral sliding movement on the machine frame. 50 At the left hand extremity of this plate is a bracket 2, at the upper extremity of which is pivoted the awl segment 4 carrying the awl 5. The awl segment 4 is suitably actuated, to give the awl a vertical oscillatory 55 movement, by a segment arm 6 which is

properly actuated from a driving cam. Shiftably mounted on the plate 1, and adjustable by means of a screw 7^a is the plate 7. Pivoted to this plate at 8 is the feed-adjusting lever 9. This feed-adjusting lever 9 is provided with a forwardly directed arm 9^a projecting considerably in front of the longitudinal axis of the lever 9, and pivoted on this forwardly projecting arm is a loose block 10. The outer extremity 9^b of the lever 9 projects to coöperate with a segment 11. This segment may be provided with the apertures 11^a with which coöperate plugs or pins 11^b, the latter being adapted to fit in any of the apertures 11^a, and afford 60 stop members which coöperate with the extremity 9^b of the adjusting lever to retain it in adjusted position. The segment 11 may be suitably calibrated as a means for indicating to the operator the various adjustments for length of stitch. The awl-shifting lever 12 is pivoted at 12^a, and has at its rearward end a roller 14 which is adapted to coöperate with a suitable driving cam 15, by virtue of which horizontal oscillatory movement is imparted to lever 12 on its pivot point 12^a. The forward arm of lever 12 is provided with an arcuate slot 12^b, in which slot the loose block 10 slides, the sides of the said block having close contact with the 65 sides of the slot. By virtue of this arrangement, as is well known in the art, the oscillatory movement imparted to lever 12 is transmitted to the sliding plate 1 through awl-adjusting lever 9, the position of the 70 loose block 10 relative to the pivot point 12^a determining the length of throw imparted 75 by lever 12 to plate 1.

When it is desired to secure a long stitch, the adjusting lever 9 is swung forwardly, so 80 as to bring the loose block 10 to the extreme forward end of lever 12. With the old form of lever, such an adjustment would bring the extremity 9^b of the adjusting lever to a position where it would project out in front of 85 the machine in a space wherein it is necessary for the operator to hold the shoe upon which the machine is operating. With my improved form of lever, however, due to the positioning of the loose block 10 on the forward projection 9^a in advance of the lever, it is not necessary, in order to secure the maximum stitch, to swing the extremity 9^b of the adjusting lever to a position where 90 it will interfere with the manipulation of 100 the machine in a space wherein it is necessary for the operator to hold the shoe upon which the machine is operating. With my improved form of lever, however, due to the positioning of the loose block 10 on the forward projection 9^a in advance of the lever, it is not necessary, in order to secure the maximum stitch, to swing the extremity 9^b of the adjusting lever to a position where 105 it will interfere with the manipulation of 110 the machine in a space wherein it is necessary for the operator to hold the shoe upon which the machine is operating.

the shoe. Furthermore, I am enabled by this arrangement to materially shorten the segment 11 so that its forward end will be entirely out of the way of the operator, 5 while at the same time being able to secure an adjustment for a stitch of greater length than is securable with former adjusting arrangements. At the same time it is possible to secure, with this arrangement, all of 10 the various gradients of adjustment of stitch. It is obvious, therefore, that my invention provides means whereby the maximum length of stitch now obtainable may be considerably increased, the various gradients 15 of adjustment obtained, and an arrangement of the stitch regulating parts secured whereby they are entirely out of the way of the operator and all work presented to the action of the machine. These various considerations are of high importance in a machine of this nature which is manufactured primarily for repair purposes and in which features of adaptability and convenience are 20 of great commercial value.

25 In modern practice, it is customary to whole-sole shoes; that is repair them by adding a sole which includes both the sole proper and the shank. In applying such soles it is customary to sew the shank portion with a considerably longer stitch than the sole portion, the length of stitch being

changed by movement of the adjusting lever while the work is in the machine and while the machine is in operation. It is of obvious importance, therefore, that the manipulative means for altering the stitch be free from interference with the work and in position where it may be easily and quickly manipulated by the operator while the machine is in operation. 35

40 What I claim is:

In a machine of the class described, a stitch-regulating mechanism comprising a shiftable awl-carrying member, a pivoted shifting lever adapted to reciprocate the 45 same, an adjustable lever having pivotal connection with the awl-carrying member, said shifting lever having a forwardly extending arm, a bearing member mounted on said forwardly extending arm and having 50 shiftable engagement with the shifting lever, and means whereby said adjusting lever may be manipulated to vary the point of engagement of said bearing member relative to the fulcrum point of said shifting lever. 55

In testimony whereof I hereunto affix my signature in the presence of two witnesses, this 29th day of January, 1915.

WILLIAM R. BLAIR.
